(57) **CLAIM**

The ornamental design for a clamp, as shown and described.

DESCRIPTION

FIG. 1 is a perspective view of the clamp of the present invention;

FIG. 2 is a top plan view thereof;

FIG. 3 is a front elevational view thereof, the rear elevational view being a mirror image thereof;

FIG. 4 is a right side elevational view, the left side elevational view being a mirror image thereof;

FIG. 5 is a bottom plan view thereof;

FIG. 6 is a cross-sectional view thereof along line 6—6 of FIG. 3; and,

FIG. 7 is a cross-sectional view thereof along line 7—7 of FIG. 3.

The broken lines are for illustrative purposes only and forms no part of the claimed design.
